HAND GRIP CONTROL FOR AIRCRAFT

Filed April 29, 1931

Lewis Abraham

By *Charmac Atkinson*
Attorney

UNITED STATES PATENT OFFICE

LEWIS ABRAHAM, OF PORTSMOUTH, VIRGINIA

HAND GRIP CONTROL FOR AIRCRAFT

Application filed April 29, 1931. Serial No. 533,824.

This invention relates to a control for the throttle valve of the carburetor of an internal combustion engine and more particularly for the type of engine or motor as is employed in aircrafts.

A primary object of this invention is to provide a control means for the valve of the carburetor adapted for use upon and in conjunction with the control or joystick of the 10 aeroplane.

Other objects and advantages of the invention, and the nature of the invention will be best understood from a study of the following description, taken in connection with 15 the accompanying drawings wherein:

Figure 1 is a side elevational view of a lower portion of the joy or control stick of an aeroplane having my invention applied thereto.

Figure 2 is a longitudinal sectional view through the joy or control stick for clearly showing the control mechanism as applied thereto.

Figure 3 is a horizontal transverse sectional view taken substantially on the line 3-3 of Figure 2.

With reference more in detail to the drawings, it will be seen that 5 designates the control or joy stick of the aeroplane, and the 30 same at its lower end is provided with a fork 6. The fork 6 straddles the usual rotary shaft 7 provided therefor and journaled in suitable bearings 8. The fork 6 is pivoted to the rotary shaft 7 as at 9.

In carrying out my invention, I provide for the upper end of the joy stick 5 a hand grip which consists of a substantially cylindrical casing 10 of metal or any suitable material and provided with an outer covering 40 11 of rubber or other suitable material. The casing 10 of the hand grip is rotatable about the axis of the joy stick 5 and the lower end of the casing 10 is supported on an annular collar 12 provided exteriorly of the stick 5.

The stick 5 is of hollow construction, and has rotatable therein a control rod 13 journaled in vertically spaced bearings 14 provided interiorly of the stick 5.

The upper end of the stick 13 is integral 50 with or otherwise secured to the upper end

of the hand grip casing 10, while the lower end of the rod 13 extends through a suitable opening provided in the rotary shaft 7 and elongated longitudinally.

The lower end of the rod 13 is bifurcated 55 and at said end is pivotally connected to a wrist pin 15 journaled between the ends of a fork 16. The shank of the fork 16 extends through a slot 17 provided in the bottom of the shaft 7 and is journaled in a bearing 18 provided on the upper end of a substantially C-shaped bracket 19 that is secured at its lower end to a part of the frame 20 of the aeroplane structure.

The free end of the shank of the fork is 60 bent laterally to provide a horizontal end portion 21 to the terminus of which is pivotally connected as at 22 a fork 23 provided on the end of a flexible operating element 24 that is suitably connected with the throttle 70 valve of the carburetor, (not shown).

As is conventional the element 24 is 65 encased in a flexible sheathing 25 suitably supported as at 26 adjacent the bracket 19.

From what has been hereinbefore stated, 75 it is apparent that upon rotating the hand grip, the rod 13 will be rotated for transmitting movement to the shank of the fork 16 thus actuating the control element 24 to operate the throttle valve for controlling the 80 speed of the motor of the aeroplane.

To prevent casual rotation of the rod 13, and thus retain the throttle valve at the desired adjustment, there is keyed to the rod 13 a toothed wheel 27 and a manually operable 85 locking bolt 28 is slideable radially through a lateral opening provided in the stick 5 and at its inner end is provided with a tooth for engaging the teeth of the wheel 27 to thereby lock the rod 13 against rotative movement. 90

The locking bolt 28 may be secured in engagement with the teeth of the wheel 27, or retained out of engagement therewith to any suitable means, such as a spring pressed ball provided in a socket 29 exteriorly of the stick 95 5 and engageable with a selected one of a plurality of recesses provided in the bolt 28 as at 30.

Even though I have herein shown and described the preferred embodiment of the in- 100

vention, it is to be understood that the same is susceptible of changes, modifications and improvements within the scope of the appended claims.

Having thus described my invention, what I claim as new is:

1. In a throttle valve control, a control stick of an aircraft, a hand grip therefor and shiftable relative to the longitudinal axis of the control stick, manual means for retaining the hand grip against casual rotation and valve control means having operative connection with said hand grip.
2. In combination, a rotary shaft, a fork straddling the shaft and pivotally connected thereto, an airplane control stick connected to the fork, a control rod rotatably mounted in said stick and having an end extending into said rotary shaft, a fork arranged in said rotary shaft and having operative connection with the said end of said rod, said fork including a shank extending through a slot in the shaft, a bearing exteriorly of said shaft for said shank, and throttle valve control means having operative connection with said shank.
3. In combination, a rotary shaft, a fork straddling the shaft and pivotally connected thereto, an airplane control stick connected to the fork, a control rod rotatably mounted in said stick and having an end extending into said rotary shaft, a fork arranged in said rotary shaft and having operative connection with the said end of said rod, said fork including a shank extending through a slot in the shaft, a bearing exteriorly of said shaft for said shank, and throttle valve control means having operative connection with said shank, a hand grip rotatable on the control stick and connected to said rod for imparting rotary movement to said rod, and manual means for securing said rod at the desired fixed adjustment.

In testimony whereof I affix my signature.

LEWIS ABRAHAM.
